UNITED STATES PATENT OFFICE.

HARRY P. BASSETT, OF CYNTHIANA, KENTUCKY, AND THOMAS F. BANIGAN, OF CLIFTON HEIGHTS, PENNSYLVANIA, ASSIGNEES, BY MESNE ASSIGNMENTS, TO SAID BASSETT.

METHOD OF SPINNING ARTIFICIAL SILK.

Application filed December 12, 1925. Serial No. 75,143.

This invention relates to methods of spinning artificial silk, and more particularly to methods of twisting the strands to form a thread after the strands have been collected 5 on a spool.

In spinning artificial silk, it is advantageous to collect the strands on a spool as the tension on the strands and the speed may thus be more easily regulated. As is well known, uniformity of the silk depends on 10 the uniform tension and speed. It is desirable, however, to avoid the spindle method of twisting the strands which is usually followed when the spun silk is collected on a reel or spool. The spindle method of twisting is open to several objections, one of 15 which is the frequent breakage of the thread at the high rate of speed necessary in properly twisting the strands as they are delivered from the spindle.

In the present invention, we obtain the advantages of reel spinning without the attendant disadvantages of twisting the strands by rotation of the reel on a spindle. 20 Instead of removing the strands from the reel in the old manner, the reel is rotated in the opposite direction and the threads twisted in a centrifuge basket.

The advantages of this process are numerous. All the advantages of collecting the spun silk on a reel or spool are retained and at the same time, the attendant disadvantages of spindle twisting are eliminated. Furthermore, the speed and tension during 25 the removal of the strands from the reel is practically automatically regulated by the fact that as the diameter of the strands on the reel decreases the diameter of the cake in the centrifuge basket decreases at the same time and thus the necessity of adjustment of 30 the relative speed of the spool and the centrifuge machine is wholly or partially eliminated.

A further advantage of the invention is 35 the fact that the advantages of the spool method of spinning may be retained and at the same time, the advantages of twisting in a centrifuge machine, such as washing and the like, may also be retained.

In the accompanying drawings, we have 40 diagrammatically illustrated the steps of the process. In this showing:

Figure 1 is a diagrammatic illustration of the spinning of the silk from a spinneret, and,

Figure 2 is a diagrammatic illustration of 55 the twisting of the strands in a centrifuge machine to form a thread.

In the drawings, the reference numeral 1 designates a spinneret of the usual type by means of which a plurality of strands 2 of 60 artificial silk are projected through a precipitating bath (not shown) and collected on a spool or reel 3 mounted on a suitable shaft 4. A receptacle 5 may be arranged beneath 65 the reel to contain a suitable washing solution, a portion of the solution being taken up by the reel on each revolution to act on the strands arranged thereon. During the spinning operation, the reel is revolved in a clockwise direction, as indicated by the arrow, by any suitable driving mechanism (not shown).

After the silk has been spun on the reel, the reel is revolved in a counter-clockwise direction, as indicated in Figure 2 of the 75 drawings, and the strands carried downwardly, as indicated at 6, into a centrifuge 7. The centrifuge is of the ordinary type and is provided with a centrally arranged 80 guide 8 having an extension 9 connected to any suitable mechanism (not shown) by means of which it is reciprocated in the usual manner. A funnel 10 is arranged at the top of the guide by means of which any suitable washing solution may be passed 85 over the thread, as it is formed. As shown, the bottom of the centrifuge is provided with a suitable drain or outlet 11.

Within the centrifuge, we provide a basket 12 connected to a rotatable shaft 13 90 which extends through the bottom of the outer casing and this basket is provided with openings 14 in its side walls through which the liquid is thrown outwardly by centrifugal force causing the thread to form in a cake 15 on the side wall in the usual manner. After the thread is removed from the centrifuge basket, it is wound into skeins 95 on reels.

It will be apparent that as the thread is removed from the reel, the diameter decreases and that the length of the thread withdrawn upon each revolution of the reel therefore varies. At the same time, the cake 15 decreases in diameter as it is built up and the length of thread necessary to extend throughout a complete revolution of the cake decreases in the same proportion.

The reel and centrifuge basket may be so proportioned that this change in the length of thread necessary for one revolution of each may be directly proportional, whereby 5 governing mechanism to regulate the tension can be abolished.

It is to be understood that the form of our invention herewith shown and described is to be taken as a preferred example of the 10 same, and that various changes in the shape, size, and arrangement of parts may be resorted to without departing from the spirit of the invention or the scope of the subjoined claims.

15 We claim:

1. The herein described process which comprises spinning strands of artificial silk from a spinneret, collecting the strands on a positively rotated spool, positively rotating the spool in the opposite direction to unroll the strands, and passing the strands 20 into a centrifuge machine to twist them and form a thread.
- 20

2. The herein described process which comprises spinning strands of artificial silk from a spinneret, collecting the strands on a positively rotated spool, positively rotating the spool in a reverse direction at a regulated speed to withdraw the strands, and twisting them to form a thread. 25

3. The herein described process which comprises spinning strands of artificial silk from a spinneret, collecting the strands on a positively rotated spool, positively rotating the spool in the opposite direction to 30 unroll the strands, passing into a centrifuge machine to twist them and form a thread, and simultaneously regulating and synchronizing the the speed of the spool and the centrifuge machine during the twisting 40 operation. 35

In testimony whereof, we affix our signatures.

HARRY P. BASSETT.
